DESIGN FOR A COMBINED SIREN AND LAMP

Robert Duncan, Chicago, Ill., assignor to Federal
Electric Company, Inc., Chicago, Ill., a corpora-
tion of New York

Application July 24, 1939, Serial No. 86,212

Term of patent 7 years

To all whom it may concern:

Be it known that I, Robert Duncan, a citizen
of the United States, residing at Chicago, Cook
County, Illinois, have invented a new, original,
and ornamental Design for Combined Siren and
Lamp, of which the following is a specification,
reference being had to the accompanying draw-
ing, forming a part thereof.

Referring to the drawing:

Figure 1 is a side elevation of a combined siren
and lamp embodying my new design;

Figure 2 is a top view of the device;

Figure 3 is a front elevational view of the de-
vice; and

Figure 4 is a fragmentary view showing the
under side of the device at one end thereof.

I claim:

The ornamental design for a combined siren
and lamp, as shown.

ROBERT DUNCAN.
